UNITED STATES PATENT OFFICE.

CHESTER E. ROBERTS, OF SEATTLE, WASHINGTON.

PACKING-BOX.

1,292,883.

Specification of Letters Patent. Patented Jan. 28, 1919.

Application filed June 21, 1918. Serial No. 241,104.

To all whom it may concern:

Be it known that I, CHESTER E. ROBERTS, a citizen of the United States, residing at Seattle, in the county of King and State of Washington, have invented certain new and useful Improvements in Packing-Boxes, of which the following is a specification.

This invention relates to improvements in boxes, and more especially to boxes for packing candy, and the like.

The object of the invention is to produce a substantial and durable box, that will stand shipment and handling, and one that may be readily opened and closed to reach the contents, and a further object is to produce a box or package with a novel, slightly and unique appearance, as well as having characteristics of practical utility.

In the drawings illustrating the invention: Figure 1 is a perspective view of the box complete;

Fig. 2 is a similar view of the box, with the cover sections removed.

Fig. 3 is a longitudinal central section; Fig. 4 is a side elevation of the box.

Referring to the drawings, the numeral 1 designates the body proper of the box. This consists of the side pieces 2 and end pieces 3. There need be no distinction from a practical standpoint between the top and bottom of the box, since, as will be obvious, a reversible structure is shown, but for convenience in explanation, I will refer to the top and bottom in the logical order, as governed by the position or arrangement of the figures on the drawing. The upper and lower edges of the sides 2 are provided with shoulders 4 two on each piece, opposite each other, in a vertical line on the same piece, and opposite each other in a transverse line on the two pieces, but somewhat nearer one end of the box than the other.

The sides of the box are preferably slightly inclined from each end, toward the center, as shown, for purposes that will presently become apparent, although I wish it understood that I do not limit myself to such construction.

The numerals 7 and 8 designate the two sections that constitute the cover of the box, and the numerals 9 and 10 designate similar sections or plates, that constitute the bottom of the box in the arrangement shown in the drawings. The pieces 7 and 9 have their inner ends abutting against shoulders 4, and the pieces 8 and 10 overlap the sections 7

and 9. These are held firmly in place by oppositely disposed bails 11, which have their ends attached by nails or other means to top and bottom narrow cross pieces 12 and 13, respectively. The cross piece 13 or the piece across the bottom of the box is preferably firmly secured to the outer section 10, which comprises part of the bottom of the box, but the top cross piece is unattached to the corresponding top piece 8, thus making it possible to move the bail out of vertical position, or to position shown in dotted lines, Fig. 1, there being a very slight play between the under side of the cross piece 12 and the top section, upon which it bears. By this arrangement, after the box has once been opened, the top piece 12 can be moved slightly toward one end of the box, thus wedging or binding the two pieces which constitute the top of the box, firmly together, effecting a tight closure, and then, when it is desired to remove one or both of the top sections, the cross piece can be brought back into parallelism with the bottom cross piece, thus relieving the pressure on the top sections and facilitating an easy removal thereof.

In closing the box originally, it being understood that the bottom sections are already in place, and the cross piece 13 attached thereto, the section 7 of the top is brought into place with its inner end against the shoulders 4, on the side pieces. This leaves a space between the under side of the cross piece 12 and the top of the section 7 of the cover, about equal to the thickness of the overlapping section 8, which is then slid under the cross piece and along the inner portion of the cover section until the outer edge of the top piece is flush with the end of the box, meanwhile, due to the inclination of the upper edges of the box, from each end to the center, a wedging tendency is brought about, which firmly binds the cover sections together, then the cover sections may be temporarily held in place by brads 14, which can readily be withdrawn, so as to permit the withdrawal of one or both sections of the cover.

The sections which are intended for the bottom are attached at intervals around the edges of the body, by similar brads that are intended to be permanent, because obviously it is only necessary to open one side of the box to reach the contents, but as before stated, the construction is such that in as-

sembling the box in the first instance, either side of the body may constitute the top and of course, the other side the bottom, as may be elected and in either event, that portion which constitutes the bottom is tacked to the edges of the body proper and the cross piece attached firmly in place.

It will be noted, say for instance in connection with the top or the removable sections, that the piece that abuts against the shoulder 4 inclines slightly downward, which co-operates with the companion section, and the inclined edge of the top of the box, to bring about the wedging tendency referred to.

However, as shown in the modification in Fig. 4, the sides of the body are not inclined, and in this instance, shoulders 5 are provided in the upper edge of a depth that will bear the top section which abuts against them flush with the upper edge of the box, and the other section of the cover will then overlap the lower section and be flush with the top of the box. The bail and cross bar construction remains the same as in the preferred form, and the box may be, as in the other form, closed by brads and if desired, both cross pieces may be tacked to the overlapping piece of the top and bottom.

Having thus described my invention, what I claim is:

1. A packing box comprising a body proper formed of side and end pieces, the side pieces being provided with shoulders, top and bottom sections having their inner ends abutting against the shoulders, overlapping independent sections completing the cover, cross pieces spanning the overlapped inner ends of the top and bottom sections, and bails connecting the cross pieces.

2. A packing box comprising a body proper having end and side sections, the side sections being provided with shoulders in vertical line with each other, on each side piece, and in line transversely with each other on the separate side pieces, top sections having their inner ends abutting against the shoulders, independent top

pieces having their inner ends overlapping the first mentioned top pieces, cross pieces extending across the overlapped ends of the top and bottom pieces, and bails connecting the said cross pieces.

3. A packing box comprising side and end pieces, the side pieces being inclined slightly toward their centers from each end, and provided intermediate of their ends with shoulders, top and bottom sections having their inner ends abutting against the shoulders, whereby their movement in one direction is limited, independent top and bottom sections overlapping the first mentioned sections, cross pieces extending across overlapped ends of the top and bottom sections and bails connecting the cross pieces.

4. A packing box comprising end and side pieces, the side pieces being inclined from each end toward the center and provided with oppositely disposed shoulders, top and bottom sections abutting against the shoulders, independent top and bottom sections overlapping the first mentioned sections, a cross piece fixed to the bottom of the box and a second cross piece extending across the overlapping ends of the top sections, but detached therefrom and bails connecting the top and bottom cross pieces.

5. A packing box comprising side and end pieces, shoulders on the side pieces, a cover section abutting against the shoulders, and a second cover section overlapping the inner end of the first mentioned cover section, cross pieces extending across the top and bottom of the box, the top piece extending across the overlapped ends of the top section, and means in addition to the cross piece for securing the cover sections to the edges of the box.

In testimony whereof I affix my signature in presence of two witnesses.

CHESTER E. ROBERTS.
